P. G. JACOBSON.
RAZOR BLADE HOLDER.

APPLICATION FILED MAR. 28, 1918. RENEWED MAR. 6, 1919.

1,318,280.

Patented Oct. 7, 1919.

Inventor:
Peter G. Jacobson.

By G. R. Ensign Atty.

UNITED STATES PATENT OFFICE.

PETER G. JACOBSON, OF CHICAGO, ILLINOIS.

RAZOR-BLADE HOLDER.

1,318,280.

Specification of Letters Patent.

Patented Oct. 7, 1919.

Original application filed February 8, 1917, Serial No. 147,291. Divided and this application filed March 28, 1918, Serial No. 225,230. Renewed March 6, 1919. Serial No. 281,074.

To all whom it may concern:

Be it known that I, PETER G. JACOBSON, citizen of the United States, residing at Chicago, in the county of Cook and State of Illinois, have invented a certain new and useful Improvement in Razor-Blade Holders, of which the following is a full, clear, concise, and exact description.

My invention relates to razor blade holders and is of particular service in the formation of holders to be used in holding the blades that are to be honed, though the invention is not to be limited to this use.

My invention has for one of its objects the provision of improved means for limiting the extent to which the blade holding clamp may swing with reference to the handle carrying it. I employ a motion limiting connection engaging both the handle and the clamp.

My invention has for another of its objects the provision of improved mechanism for forcing the jaws of the blade holding clamp into engagement with the blade to be held thereby and to this end I employ transverse continuations upon the jaws and means acting upon these continuations for the purpose stated. Certain of the claims upon my invention are contained in my original application, Serial No. 147,291, filed February 8, 1917, and of which the present application is a division.

I will explain my invention more fully by reference to the accompanying drawing showing the preferred embodiment thereof and in which Figure 1 is a view in side elevation of a razor blade holder as I preferably make it; Fig. 2 is a plan view; Fig. 3 is a view on line 3—3 of Fig. 2; Fig. 4 is a view similar to Fig. 3 but with the jaws of the blade holding clamp open; Fig. 5 is a view on line 5—5 of Fig. 3; Fig. 6 is a view on line 6—6 of Fig. 4; and Fig. 7 is a view on line 7—7 of Fig. 5.

Like parts are indicated by similar characters of reference throughout the different figures.

The blade holder includes one member in the form of a blade holding clamp having jaws 1, 1 and a second member in the form of a handle 2 upon which the clamp is mounted between its front blade holding end and its rear end to swing upon the handle. The handle has forked branches 3 carrying a clamp supporting rod at their

forward ends. This rod is preferably of sectional formation, its parts being a sleeve 4 and trunnion screws 5 and 6 entering the bore of the sleeve and in threaded connection with the ends thereof. Each of the jaws has transverse continuations 7, the transverse continuations upon one jaw being interposed between the transverse continuations upon the other jaw. The tube or sleeve 4 is interposed between the continuations upon one jaw and has butt engagement with said continuations. The trunnion screws extend outwardly beyond the clamp and their stems are surrounded by said continuations and the forward ends of the fork branches 3 of the handle, whereby the clamp and handle are assembled and the clamp may swing upon the handle at a point between the forward and rear ends of the clamp.

The rear ends of the clamp jaws are pivotally united by a shaft 8 passing therethrough and which shaft carries a roller 9 for supporting the clamp in proper position upon the hone. The extent to which the clamp may swing upon the handle is limited by the connections 10 that are continuations of the shaft 8 and whose outer ends have lost motion engagement with the handle parts 3, preferably by operating in slots 11. When this construction is adopted, the shaft 8 is desirably made in two parts as indicated in Fig. 5.

The openings in the jaw continuations through which the trunnion screws 5 pass are preferably in the form of slots extending longitudinally of the clamp and along which said screws may be moved bodily and longitudinally with reference to the clamp. This may be done by holding the clamp in one hand and the handle in the other and moving the clamp toward or away from the handle. When the clamp is pulled out as far as possible, the screws are at the rear of the slots (Fig. 4) and these slots are then most out of register and the jaws of the clamp are then farthest apart to permit of the insertion of a blade 12. When the screws are forced to the front ends of the slots, the slots are brought more into register and the jaws are consequently forced together (Fig. 3) to grip the inserted blade 12. The front end of one of the slots is continued laterally of the slot in one direction and the front end of the other slot is continued laterally in

an opposite direction whereby a locking formation is produced to hold the shaft when the blade is clamped, the shaft being prevented from working backward. The 5 rear ends of the slots may be similarly curled to cause the shaft to be held when the jaws are separated but such formation of the rear ends of the slots is not essential. The jaws are resilient and are therefore firmly 10 applied to the blade.

While I have herein shown and particularly described the preferred embodiment of my invention I do not wish to be limited to the precise details of construction shown 15 as changes may readily be made without departing from the spirit of my invention, but having thus described my invention I claim as new and desire to secure by Letters Patent the following:—

20 1. A razor blade holder including a pair

Copies of this patent may be obtained for five cents each, by addressing the "Commissioner of Patents, Washington, D. C."

of jaws having transverse continuations provided with longitudinal slots that are out of register when the jaws are open; and a rod passing through said slots and movable longitudinally thereof to cause said slots to be 25 moved into register to apply the jaws to the blade to be held thereby.

2. A razor blade holder including a pair of jaws having transverse continuations provided with longitudinal slots that are 30 out of register when the jaws are open; a rod passing through said slots and movable longitudinally thereof to cause said slots to be moved in register to apply the jaws to the blade to be held thereby; and a handle 35 carrying said rod.

In witness whereof, I hereunto subscribe my name this 30th day of March A. D., 1917.

PETER G. JACOBSON.
